UNITED STATES PATENT OFFICE.

JOHN O. WARD, OF SANTA MARIA, CALIFORNIA, ASSIGNOR OF ONE-HALF
TO PEMBROKE W. JONES, OF SANTA MARIA, CALIFORNIA.

IRONING-BOARD.

No. 881,254.

Specification of Letters Patent.

Patented Sept. 18, 1906.

Application filed November 21, 1905. Serial No. 288,410.

To all whom it may concern:

Be it known that I, JOHN O. WARD, a citizen of the United States, residing at Santa Maria, in the county of Santa Barbara and State of California, have invented a new and useful Ironing-Board, of which the following is a specification.

This invention relates to ironing-boards, and has for an object to provide a device of the class embodying new and improved features of adaptability, convenience, rigidity, and efficiency.

A further object of the invention is to provide an ironing-board embodying improved means for attaching to a table of the usual construction and affording unusual rigidity and security.

A further object of the invention is to provide an ironing-board embodying improved means for adjusting to various thicknesses of table-tops and including no parts to be lost or mislaid.

With these and other objects in view the present invention consists in the combination and arrangement of parts, as will be hereinafter fully described, shown in the accompanying drawings, and particularly pointed out in the appended claim, it being understood that changes in the form, proportion, size, and minor details may be made without departing from the spirit or sacrificing any of the advantages of this invention.

In the drawings, Figure 1 is a view of the improved ironing-board in side elevation applied to a table. Fig. 2 is a view of the board in side elevation and folded. Fig. 3 is a bottom plan view of the board folded. Fig. 4 is a detail sectional view. Fig. 5 is a detail view of the hinge.

Like characters of reference indicate corresponding parts in all of the figures of the drawings.

In its preferred embodiment the improved ironing-board forming the subject-matter of this application comprises a tapered table member 10, provided with a longitudinal slot 11, formed in its wider end, and with spurs, which for convenience and economy may be the screws 12, extending upward from its upper surface upon each side of the slot.

To the under surface of the table and adja-

cent the slot is secured one leaf of a hinge, as 13, the other leaf 14 being provided with a slot 15. A leg member 16 is provided with a notch 17, forming a shoulder 18 for engaging the upper surface of a table, as 19, and in opposed relation to the spurs 12. The leg is secured to the table by means of a bolt 20, slidably engaged within the slot 15, and retained as by the nut 21.

To adapt the device for application to table-tops of different thicknesses, it is necessary simply to loosen the nut 21 on the bolt 20 and slide the leg relatively to the leaf 14 in a direction indicated by the slot 15 thereof to decrease or diminish the interval between the plane of the table member 10 and the shoulder 18. When the desired interval has been provided, the bolt may be tightened to lock the parts at the desired adjustment. The ironing-board may then be applied to or removed from a table-top simply by relative swinging movement of the top 10 and leg 16. Further adjustment of the leg with reference to the hinge-leaf 14 is not necessary unless it is desired to apply the device to a table-top of a different thickness.

Having thus described the invention, what is claimed is—

An ironing-board comprising a table 80 formed with a longitudinal slot at one end, engaging spurs projecting upward from the upper surface of the table at opposite sides of the slot, a leg member formed with an engaging shoulder, said leg member projecting edge-wise through the slot in the table, a hinge having its upper leaf secured to the under surface of the table adjacent the slot, and having its lower leaf extending downward along the upper edge of the leg member and formed 85 with a longitudinal slot, and a bolt extending through the slot and edge-wise through the leg member, said bolt being provided with a tightening-nut, substantially as described.

In testimony that I claim the foregoing as 90 my own I have hereto affixed my signature in the presence of two witnesses.

JOHN O. WARD.
